TYPE RIBBON FEED DEVICE FOR RACE
TOTALIZATOR TICKET ISSUERS

Awdry Francis Julius, Sydney, New South Wales, Australia, and George Alfred Julius, deceased, late of Sydney, New South Wales, Australia, by Eva Dronghsia Odierna Julius, Killara, near Sydney, New South Wales, Australia, and Awdry Francis Julius and Russell Stuart Hicks, Sydney, New South Wales, Australia, executors, assignors to Automatic Totalisators Limited, Sydney, New South Wales, Australia

Application June 30, 1948, Serial No. 36,164
In Australia June 30, 1947

2 Claims. (Cl. 101—336)

1

This invention is referable to race totalisator ticket issuers of the type broadly classifiable as incorporating an operating handpiece which on suitable manipulation, causes closure of an operating circuit for a "win," "place" or other adding unit for a particular competitor, thus to record a required ticket issuing transaction relative to that competitor. In addition to being instrumental in the recording of each transaction, operation of the handpiece also conditions printing or type devices in readiness for printing the required ticket. Operation of the handpiece also actuates interlock means for locking the handpiece against further operation until the printed ticket has actually issued, and is also instrumental in closing the circuit of a magnetic clutch associated with the drive shaft of a continuously running motor. Closure of the clutch circuit, and consequent drive through the clutch, causes rotation (through worm or other gearing) of a cam shaft, which on completion of a single revolution is halted by automatic opening of the clutch circuit.

A revolution of the mentioned cam-shaft (working through the agency of suitable gearing, cam-followers, bell-cranks, links, levers, or the like) operates:

(a) A platen or backing pad whereby a ticket portion of a ticket strip or roll is pressed towards the previously conditioned type devices, an inked ribbon being disposed between the type and the ticket face to be printed.

(b) Friction grip feed rolls or like devices whereby a strip of ticket paper is fed through a feed chute, and into and through a ticket printing station.

(c) Means whereby an inked ribbon is "inched" or traversed a short distance through the printing station by turning a winding reel therefor; and,

(d) A guillotine blade or scissors to cut the just printed ticket portion from the ticket strip.

"Veeder" or other counting mechanism may also be operated as a direct, or indirect, result of the cam shaft revolution to record a total printed ticket output of the issuer.

The present invention is concerned with means for travelling an inked ribbon through a printing station forming part of a ticket issuer of the general type indicated above.

Existing ribbon feeding devices comprise a winding reel which for each actuation of the issuer cam shaft is turned through a small angle to give short step-by-step motion of the ribbon through the printing station. These prior ar-

rangements are defective in that provision has only been made for automatically winding the ribbon in one direction, and when the ribbon has been completely wound in this direction it has been necessary to rewind the ribbon manually, back from one reel to the other. This frequently causes serious delay when the ribbon runs out during a busy period of ticket issuing.

The object of this invention is to overcome the 10 stated disability by the provision of simple ribbon feed devices in which, when the ribbon has completely unwound from one reel on to a second reel, the reel drive is automatically reversed and the ribbon slowly rewinds in reverse sense, thus 15 enabling both the forward and reverse traverses of the ribbon to be effective working traverses.

The invention may be summarised as the provision, in or for a race totalisator ticket issuer, of type ribbon feed devices preferably comprising, 20 a pair of independently revoluble reels, intermittent unidirectional drive devices for both of the reels, a pair of cam levers having "throws" (or humped portions) able to idle the drive devices in respect of either one of the reels, a pair of ribbon 25 guide or "throw-over" rollers mounted respectively on the cam levers, a link pivotally connected to both of the levers, and a spring-loaded toggle able to impose either one of two stable and effective working positions on the cam levers.

30 An example of the invention is illustrated by the drawings herewith.

Figure 1 is a side elevation of a winding reel assembly.

Figure 2 is a plan projected from Figure 1.

35 Figure 3 is a sectional end elevation taken substantially on line 3—3 in Figure 1.

Figures 4 and 5 are schematic side elevations of the assembly shown in the remaining figures, showing the main parts in their two stable working positions respectively.

40 The ribbon feeding means comprise a pair of winding reels independently revoluble on parallel shafts 6 and 7 mounted on a frame 8 adapted for conventional mounting on an issuer chassis, indicated at 9. Each of these reels consists of a central barrel (10 and 11) with flanges (12 and 13) at one end thereof. The reel barrels are furnished with conventional means (not shown) for attachment of inked ribbon ends thereto. 45 Each of the reels has a ratchet drive wheel (14 and 15) rigidly mounted concentrically thereon. These drive wheels are preferably about equal in diameter to the reel flanges and function as ribbon guide flanges for the reels in the same manner as flanges 12 and 13. The ratchet wheels

are adapted for respective engagement by a pair of drive pawls 16 and 17, and a pair of stop pawls 18 and 19 able to prevent back rotation of the ratchet wheels. The two stop pawls may be formed as a single element from a piece of spring wire having a short helical coil 20 therein which forms a convenient mounting for the element by fitting loosely on a pin 21 or the like homed in the frame 8.

The two drive pawls are pivotally mounted, by way of holed U-shaped end portions 22 and 23, on a pin 24 carried by a U-shaped swing bracket 25 which is radially oscillatable about a pin 26. Bracket 25 is disposed between the winding reels. Each of the drive pawls is furnished with a loading spring (27 and 28) which influences it to remain in driving engagement with its respective ratchet wheel. The swing bracket 25 has one end of a driving link or pitman 29 pivoted thereto. The other end of this link is adapted to be reciprocated by a cam, crank or the like keyed on or otherwise driven from the issuer cam shaft.

Two ribbon guide of "throw-over" rollers 30 and 31 are respectively mounted on a pair of plate-like cam levers 32 and 33 which are freely mounted on the respective reel shafts 6 and 7. The rollers 30 and 31 are thus orbitally movable relative to their respective reels. The cam levers are connected by a link rod 34 pivotally connected to both levers at 35 and 36. The cam lever 32 has two cam lobes 37 and 39 and the cam lever 33 has two cam lobes 38 and 40 thereon. The cam throws have a slightly greater radius than the ratchet drive wheels and are so arranged that upon being placed in their limit positions, as shown to the right of Figure 4 or the left of Figure 5, they are able to hold the drive pawl and the stop pawl for the particular ratchet wheel clear thereof. In such condition these two pawls "idle" or ride ineffectively on their respective cam throws and thus leave the associated reel freely rotatable.

One of the cam levers (32 in the drawings) has a diametrically drilled boss 41 pivotally mounted thereon. A toggle pin 42 pivotally anchored by one end (about pin 43) to the frame 8, has its other end slideable in the boss drilling. A compression spring 44 is sleeved on the toggle pin between the frame pivot end thereof and the boss. The pivot centres of the toggle pin and the cam lever with which it is associated, are so spaced apart that on rotation of the cam lever the toggle spring passes resistingly towards and unstable dead centre position in which the pivot centres of the cam lever, the toggle pin frame connection and the drilled boss are in line. Equi-angularly on either side of this line are two limit positions (as shown by Figures 4 and 5 respectively) which either because of stops being provided or because the expansive thrust of the spring 44 falls to zero, define the limits of angular rotative movement of both cam levers. Both levers are thus affected by reason of their being joined by link 34. One of these limit positions (as shown by Figure 4) defines the working position for cam lever 32 and the idling position for cam lever 33, and the other limit position (as shown by Figure 5) defines the idling position for lever 32 and the working position for lever 33. When either of the cam levers is in idling position its cam throws are so placed as to render the two pawls, for the related ratchet wheel, ineffective as described above.

Assuming lever 32 is in working position (Figure 4) then its reel is conditioned to wind

up the inking ribbon 45, drawing it from the idling, that is freely revoluble, reel associated with lever 33. The ribbon passes round the throw-over rollers 30 and 31 as shown. Upon reciprocation of the driving link or pitman 29, due to rotation of the issuer cam shaft in performance of a ticket production, the drive pawl 16 partly rotates the reel barrel 10. This action continues with subsequent ticket production cycles until the ribbon is fully unwound from reel barrel 11. Upon continued drive to barrel 10 the ribbon is tensioned, when it is no longer able to unwind from barrel 11, because its end is anchored thereto, and when this tension is imposed as a side thrust on roller 31 and is such as to overcome the loading effect of the toggle spring (by a pull transmitted through lever 33, link 34 and lever 32) the toggle passes through its dead centre position, moving the throw-over rollers orbitally, thus setting cam lever 32 in idling position (Figure 4) wherein its stop and drive pawls (18 and 16) are rendered ineffective, by being held of ratchet 14 by the cam throws 39 and 37, and placing cam lever 33 in working position so that its ratchet 15 becomes an effective driver, and the ribbon is then wound upon barrel 11 until completely unwound from barrel 10 when tensioning of the ribbon about roller 30 again effects the changeover as described above.

What we claim is:

1. In a type ribbon feed device for a race totalizator, a frame adapted to be secured to a ticket issuer chassis, a pair of parallel shafts fixed on said frame, a pair of winding reels respectively mounted on said shafts and freely rotatable thereon, oppositely positioned ratchet wheels fixedly mounted on and forming parts respectively of said winding reels, an oscillatory bracket pivoted at one end on said frame between said winding reels, two oppositely extending drive pawls both pivoted on the free end of said oscillatory bracket and selectively engageable respectively with said ratchet wheels, springs mounted on said oscillatory bracket for biasing said drive pawls into engagement with said ratchet wheels, an operating link pivotally connected to the free end of said oscillatory bracket, reverse rotation preventing pawls pivotally mounted on said frame and selectively engageable with said ratchet wheels, two cam members freely mounted respectively on said shafts, said cam members each having two lobes respectively engageable with the associated reverse rotation preventing pawl and the associated drive pawl to hold same out of engagement with the associated ratchet wheel, a link interconnecting said cam members for conjoint operation, a pair of throw-over rollers respectively mounted on said cam members and adapted to remain constantly in contact with a type ribbon wound on both of said reels, and a spring loaded toggle device pivotally mounted on the frame and connected to one of said cam members for holding said cam members in either a first position wherein the lobes on one cam member are respectively in engagement with the associated drive and reverse rotation preventing pawls, or in a second position wherein the lobes on the other cam member are respectively in engagement with the associated drive and reverse rotation preventing pawls.

2. In a type ribbon feed device for a race totalizator, a frame adapted to be secured to a ticket issuer chassis, a pair of parallel shafts fixed on said frame, a pair of winding reels respectively mounted on said shafts and freely ro-

tatable thereon, oppositely positioned ratchet wheels fixedly mounted on said shafts and freely rotatable thereon, oppositely positioned ratchet wheels fixedly mounted on and forming parts respectively of said winding reels, an oscillatory bracket pivoted at one end on said frame between said winding reels, two oppositely extending drive pawls both pivoted on the free end of said oscillatory bracket and selectively engageable respectively with said ratchet wheels, springs mounted on said oscillatory bracket for biasing said drive pawls into engagement with said ratchet wheels, an operating link pivotally connected to the free end of said oscillatory bracket, reverse rotation preventing pawls pivotally mounted on said frame and selectively engageable with said ratchet wheels, two cam members freely mounted respectively on said shafts, said cam members each having two lobes respectively engageable with the associated reverse rotation preventing and the associated drive pawl to hold same out of engagement with the associated ratchet wheel, a link interconnecting said cam members for conjoint operation, a pair of throw-over rollers respectively mounted on said cam members and adapted to remain constantly in contact with a type ribbon wound on both of said reels, and a spring loaded toggle device for holding said cam members in either a first position wherein the lobes on one cam member are respectively in engagement with the associated drive and reverse rotation pawls, or in a second position wherein the lobes on the other cam member are respectively in engagement with

the associated drive and reverse rotation preventing pawls, said toggle device comprising a boss rotatably mounted on one of said cam members and having a diametrical hole therethrough, a pin mounted on said frame, a toggle rod having a shoulder thereon pivotally mounted on said pin and extending through the hole in said boss and oscillatable between either of two said positions, and a compression spring surrounding said toggle rod and positioned between the shoulder thereon and said boss.
